Emmanuel Scheyer.

UNITED STATES PATENT OFFICE

ATTILIO MARELLI, OF UNION CITY, NEW JERSEY

MILK BOTTLE LOCK

Application filed January 18, 1930. Serial No. 421,834.

This invention relates to a milk bottle lock of the type which is opened when the door of the house or apartment is opened. One part of the lock is fastened to the door and the other to the side of the door frame. One of the advantages of this invention is the simplicity of the construction. Another advantage is that the parts of the lock when not in use lie flat against the door and door frame. A still further advantage is that the lock can be constructed to hold one or a plurality of milk bottles. A lock designed, in accordance with the present invention, to hold a number of milk bottles can still be used to hold securely less milk bottles than its capacity.

The lock is composed essentially of two hinges, one in the form of a U shaped hasp and the other comprising a bar latch adapted to close the open end of the hasp. The milk bottles are held in the U shaped hasp. When the door is opened, the bar latch is pulled away from the hasp.

Other objects and advantages will become apparent upon further study of the description and drawings in which:—

Fig. 1 is a front elevation showing a lock, in position on a door hinged at its left, with bottles held in the lock, Fig. 2 is a front elevation of a lock in closed position on a door hinged at its right, Fig. 3 is an enlarged front view of the lock shown in Fig. 1, without the bottles, taken along line 3—3 of Fig. 4, Fig. 4 is a plan view of the lock taken along line 4—4 of Fig. 3, the bottles being indicated by dashed lines, Fig. 5 is an enlarged view along line 3—3 of Fig. 4 just taken for sufficient length along this line to show the locking end of the hasp. The front wall of the spring casing in Fig. 5 is omitted to show the construction more clearly. Fig. 6 is a view taken along line 6—6 of Fig. 4, neglecting the door and showing a rear view of the spring mounting of the latch member, said member being in released position.

The door 7 has securely fastened to it hinge leaf 8. Leaf 8 has a raised housing 9 in which tension spring 10 reposes. The right end of spring 10 (Fig. 6) is fastened inside housing 9, while its left end is looped through a hole in latch member 11. Member 11 is loosely mounted on pin 14 held in leaf 8. Spring 10 normally holds latch member 11 against the face of door 7 as shown dotted in Fig. 4, a portion of member 11 being broken away. Member 11 is formed with a bottom groove 13 and a top groove 12 for a purpose hereinafter specified. The outer end of member 11 is provided with a finger hold 15.

Hinge leaf 16 is securely fastened to door frame 17. Hinge pin 18 is mounted upon hinge leaf 16 and hasp 19 is mounted upon pin 18. Torsion spring 20, mounted upon pin 18, normally tends to swing and hold hasp 19 up against door frame 17 as shown in dotted position in Fig. 3. The free ends of hasp 19 are provided with forks 21. Adjacent to each fork 21, there is mounted a casing 22 containing a flat spring 23 which normally presses a dog 24 up through a hole 70 provided in hasp 19, providing in effect a spring catch.

When the milk bottle lock is not in use, hasp 19 is in upper position against the side of the door frame 17, and latch member 11 is pressed flat in horizontal position against the front of the door.

When milk bottles 25 are to be locked in front of the door, hasp 19 is turned down to horizontal position, said hasp being so mounted on the door frame, that in this position the hasp is on line with the neck of the bottles. The necks of the bottles are then slid into the open end of hasp 19.

Now when the bottles are slid into hasp 19, latch member 11 is turned forward so that it enters forks 21, the forward edge of latch member 11 riding upon the rounded top of dogs 24, pressing said dogs down until they spring up into bottom groove 13 of the latch

member. Latch member 11 is now held against swinging motion and closes the open end of the U shaped hasp 19, locking bottles 25 therein. When door 7 is now opened by being swung inward away from hasp 19, latch member 11 is slid out of forks 21, thereby making it possible to slide bottles 25 out of hasp 19.

When the door 7 is mounted so that its 10 hinges are on its right hand side, the milk bottle lock is mounted at the left of the door as in Fig. 2. In this case, in order that latch member 11 swing inward away from the free edge of the door, said member with its hinge leaf 8 is mounted upside down from that 15 shown in Fig. 3, bringing groove 13 to the top and causing groove 12 to be the one which engages with dogs 24.

By making the legs of hasp 19 longer, more 20 bottles could be accommodated. If less bottles than the full capacity of the lock are placed therein, still they cannot be removed. The device can also be constructed with a dog 24 in only one of the forked ends of the 25 hasp.

I claim:

1. A milk bottle lock comprising a member 30 hinged to a door, and a member hinged to the door frame, the pivotal axes of said members being substantially at right angles to each other, and locking means upon said members for locking them to each other when brought together, said members being suitably formed to enclose a suitable area when locked to each other to enable them to lock a milk bottle by its neck between them.

2. A milk bottle lock comprising a latch member pivotally mounted upon a door; and a 40 U-shaped hasp member hingedly mounted upon the door frame adjacent said latch member, said latch member adapted to be placed across the open end of the hasp, means for locking said latch member to the hasp when placed across the open end of same, the area enclosed between said members being suitable for said members to lock a milk bottle or bottles by the neck between them.

3. A milk bottle lock comprising a latch member pivotally mounted upon a door, a 50 U-shaped hasp member hingedly mounted upon the door frame, said latch member adapted to be placed across the open end of the hasp for enclosing a suitable area to enable said members to lock a milk bottle by its neck between them, and locking means located near the outer end of the hasp, said latch member being provided with a groove for locking engagement with said means, said locking means sliding through the groove and releasing the latch member when said member is pulled away by the door upon being opened.

4. A milk bottle lock comprising a member 60 pivotally mounted upon a door, and a member pivotally mounted upon the door frame, said members being movable into engagement

with each other, means for automatically locking said members together when brought into engagement said members being suitably formed to enclose an area between them when locked to enable them to lock a milk bottle 70 by its neck between them, said locking means being suitably constructed to allow said member mounted upon the door to be withdrawn from the locking engagement by the door as it is opened.

5. A milk bottle lock comprising a latch member and a U-shaped hasp member, one of said members being pivotally mounted upon the door and the other upon the door frame, the outer end of one of the legs forming the 80 U of the hasp being forked, said latch member being movable to a position across the open end of the hasp into engagement with said forked end and locking means for automatically locking the latch member in said 85 forked end when said latch member is placed therein, said members being suitably formed, when placed in locking position to lock a milk bottle by its neck, said member mounted upon the door being withdrawn from the other 90 member by the door as it is opened.

6. A milk bottle lock comprising a latch member pivotally mounted upon a door and having a groove running along it substantially at right angles to its pivotal axis, a U 95 shaped hasp member pivotally mounted upon the door frame, the outer end of one of the legs forming the U of the hasp member being forked, said latch member being movable to a position across the open end of the hasp member into said forked end, and a spring catch projecting into said forked end adapted to snap into said groove when the latch member is moved into the forked end for effecting a locking engagement of the latch and hasp members, said members being suitably formed, when placed in locking position to 100 enclose a suitable area to enable them to lock a milk bottle by its neck, when said neck is placed in said area, said latch member being withdrawn from the forked end by being pulled therefrom by the door, as it is opened, the spring catch sliding in the groove as the latch member is withdrawn.

7. A milk bottle lock as claimed in claim 6 in which the latch member is in the form of a rod pivotally mounted at one end upon the door and having a groove running along its length.

8. A milk bottle lock comprising a rod 120 pivotally mounted at one end near the free edge of a door, said rod having a groove running along its length on a pair of opposite sides, a U shaped hasp pivotally mounted upon the side of the door frame adjacent the free edge of the door, the outer end of one of the legs forming the U of the hasp being forked, said rod being swingable to a position across the open end of the hasp into said 125 forked end, and a spring catch projecting 130

into said forked end adapted to snap into one of said grooves when the latch is moved into the forked end, the second of said grooves adapting the rod to engage the spring catch ⁵ when the rod is mounted opposite hand upon a door having its free edge opposite hand to the former free edge.

Signed at Union City in the county of Hudson and State of New Jersey this 14th day of ¹⁰ January, A. D. 1930.

ATTILIO MARELLI.
